UNITED STATES PATENT OFFICE

130,589

DESIGN FOR AN ELECTRIC ATTACHMENT CAP

George R. Goodwin, Pawtucket, R. I., assignor to
Royal Electric Company Incorporated, Paw-
tucket, R. I., a corporation of Massachusetts

Application September 22, 1941, Serial No. 103,442

Term of patent 7 years

To all whom it may concern:

Be it known that I, George R. Goodwin, a citizen of the United States, residing at Pawtucket, in the county of Providence and State of Rhode Island, have invented a new, original, and ornamental Design for an Electric Attachment Cap, of which the following is a specification, reference being had to the accompanying drawing, forming part thereof.

Figures 1 and 2 are side and edge elevational

views, respectively, of the cap showing my new design.

Figures 3 and 4 are top and bottom views, respectively, of the same.

Figure 5 is a view similar to Figure 1, but showing the cap in the position of use.

I claim:

The ornamental design for an electric attachment cap, as shown.

GEORGE R. GOODWIN.
